UNITED STATES PATENT OFFICE.

CARL J. DEXTER, OF LA FAYETTE, INDIANA.

BUILDING-BLOCK MOLD.

Application filed September 21, 1927. Serial No. 220,988.

The present invention is directed to improvements in building block molds.

The primary object of the invention is to provide a device of this character so constructed that blocks can be quickly formed and provided with mortar retaining grooves across both sides, or one side, and across the ends thereof.

Another object of the invention is to provide a mold of this nature so constructed that the groove forming ribs can be easily and quickly withdrawn from the block during the molding process, the construction and mounting of the ribs in the mold being such that the material, when poured into the mold and tamped will not cause the ribs to sag or warp.

With these and other objects in view, this invention resides in the novel features of construction, formation, and arrangement of parts to be hereinafter more fully described, claimed and illustrated in the accompanying drawings, in which,—

Figure 1 is a top plan view of the mold.

Figure 2 is a side elevation.

Figure 3 is a longitudinal sectional view through the mold.

Figure 4 is a transverse sectional view through the mold.

Figure 5 is a perspective view of the block formed by the mold.

In carrying out my invention a mold 1 is used and consists of front and rear sides 2 and 3, respectively, which have their inner faces provided with a plurality of vertically spaced grooves 4 which may vary in number, as desired. These sides have their lower edges resting upon a bottom or base plate 5 which has formed therein openings 6 in which the cores 7 are movable, said plate being supported in any approved manner. The cores, of course can be raised and lowered through any suitable mechanism.

The cores, as will be of course understood, are for the purpose of providing the finished block with air spaces and to permit the electrical conductors to be easily led through a wall formed from the blocks.

A pallet 8 rests upon the bottom plate and is provided with openings 9 which coincide with the openings 6 to accommodate the cores 7, as clearly shown in Figures 3 and 4.

Mounted between the sides 2 and 3 are end plates 10 having transversely disposed vertically spaced ribs 11 upon their front faces,

said plates being mounted upon the confronting faces of the heads 11' which are slideable upon the pallet 8 in order that the plates 10 may be moved inwardly or outwardly when desired. It will be obvious that the ribs 11 will form transverse grooves in the ends of the block during the molding process.

In order to provide longitudinal grooves in the sides of the blocks ribs 12 are employed which consist of bodies 13 shaped to conform to the shape of the grooves 4 and in which they are slidably engaged, said bodies in this instance being shown provided with dove tailed heads 14, but it will be of course understood that the shape of the heads may be varied, as desired.

The ribs are of such length that they will extend between the plates 10 and heads 11' and in which they slide, said plates and heads having their side edges formed with openings 15 corresponding in shape to said ribs.

In order that the ribs 12 may be simultaneously withdrawn a member 16 connects one of their ends, power for moving the member being derived from any suitable source.

As shown in Figure 5, a finished block 17 is illustrated which is provided with longitudinal side grooves 18 which are formed by the ribs 12 and end grooves 19 formed by the ribs 11, there being air spaces 20 formed by the cores 7.

In operation, the cement is poured into the mold in a semi-solid state and at which time the ribs 12 extend fully through the plates 10. This material is stamped as it is poured into the mold and will have impressed in its side and ends grooves corresponding in shape to the ribs 11 and 12. Owing to the fact that the bodies 13 are seated in the grooves 4 of the sides, the ribs 12 will be effectively braced throughout their length in order to prevent sagging of the ribs during the tamping operation, and in this manner the grooves 18 will be smoothly finished and in true parallelism. This not only adds to the finish of the block, but will permit the ribs 12 to be withdrawn with comparative ease. It may be added that after the cement or aggregate has been thoroughly tamped a metal plate may be placed upon the upper end of the mold and subjected to pressure to enhance the appearance of the front face of the block.

It will be apparent that blocks formed in this manner and with the grooves are so arranged that they may be laid and firmly

bonded by cement or mortar which will flow into the various grooves as the wall is being built.

After the block becomes substantially hard in the mold and the ribs 12 have been withdrawn from engagement with the sides thereof, the plates 10 are moved outwardly, whereupon the front side 2 is swung open and the block can be readily removed from the mold upon the pallet 8. It will be of course understood that the cores 7 are withdrawn previous to removal of the block. The openings 20 not only produce air spaces but extend into the block for a considerable distance so that when the block is finished the ends of the spaces will be relatively thin in order that openings can be easily formed therein to permit electrical conductors to be installed in the wall formed from the blocks.

It may be desired at times to provide longitudinal grooves in one side only of a block, and in which event the grooves 4 upon one of the sides will be filled with plain bodies, that is bodies without heads similar to the heads 13.

Having thus described the invention, I claim:

1. A mold for forming building blocks, comprising a bottom plate, spaced sides resting upon said plate, end plates adjustable toward and away from each other between

the sides, said sides having grooves formed therein, ribs including bodies slidably fitted in the grooves and having heads projecting inwardly therefrom to provide mortar receiving grooves in the sides of a block. 35

2. A mold for forming building blocks, comprising a bottom plate, spaced sides mounted upon the plate and having grooves formed in their confronting faces, end plates 40 mounted between the sides, ribs movable through the end plates and including bodies for slidably engaging the grooves, said bodies having heads thereon for forming correspondingly shaped grooves in a side of the 45 block.

3. A mold for forming building blocks comprising a bottom plate, sides mounted upon the bottom plate and having grooves formed in their confronting faces, end plates 50 adjustably mounted between the sides, ribs slidably in the end plates and having bodies for slidably engaging said grooves, said bodies having heads carried thereby for forming correspondingly shaped grooves in the 55 sides of a block, said end plates having ribs for forming grooves in the ends of the blocks, and cores movable through the bottom plates for forming air spaces in the blocks. 60

In testimony whereof I affix my signature.

CARL J. DEXTER. [L. S.]
